United States Patent Office

Des. 222,977
Patented Feb. 15, 1972

222,977

WORK DESK OR SIMILAR ARTICLE FOR USE IN A HOSPITAL OR THE LIKE

Ralph E. Schubert and Alexander Bally, Pittsburgh, Pa.,
assignors to CGR Medical Corporation, Cheverly, Md.

Filed Sept. 24, 1970, Ser. No. 25,178

Term of patent 14 years

Int. Cl. D6—04

U.S. Cl. D33—7

FIG. I.

FIG. 1 is a front perspective view of a work desk or similar article for use in a hospital or the like, showing our new design;

FIG. 2 is a front elevation view thereof;

FIG. 3 is a side elevation view thereof, the opposite side appearing substantially the same as the side shown;

FIG. 4 is a top plan view thereof; and

FIG. 5 is a rear elevation view thereof.

We claim:

The ornamental design for a work desk or similar article for use in a hospital or the like, substantially as shown and described.
